UNITED STATES PATENT OFFICE.

GEORGE A. STARKWEATHER AND DEL D. HUTSON, OF FORT MADISON, IOWA.

WASHING-MACHINE.

1,127,305.

Specification of Letters Patent.

Patented Feb. 2, 1915.

Application filed March 26, 1914. Serial No. 827,423.

To all whom it may concern:

Be it known that we, GEORGE A. STARKWEATHER and DEL D. HUTSON, citizens of the United States, residing at Fort Madison, in the county of Lee and State of Iowa, have invented certain new and useful Improvements in Washing-Machines, of which the following is a specification.

My invention relates to new and useful improvements in washing machines and as its principal object aims to provide an apparatus of this character which may be cheaply manufactured, will be durable and efficient in its action and may be easily cleaned after use.

An object of equal importance with the foregoing is to provide a washing machine consisting essentially in a body portion which is formed in the nature of a tub, and is removably mounted in a supporting frame having a bracket in which a lamp or similar heating element may be placed for the purpose of heating the water in the tub so that the tub acts not only as a receptacle for the clothes but serves also as the boiler.

A further object is to provide for the tub or body of the washing machine a removable cover which carries the operating mechanism for a plurality of vertically reciprocable pounders.

A still further object is the provision of a novel form of clothes pounders which consists essentially in a shaft or stem having a slidably terminally disposed suction cup which is adapted to be yieldably engaged with the clothes through the agency of a helical spring which is wound around the shaft and normally holds the cup at the extreme lower terminal of the shaft.

The above and additional objects are accomplished by such means as are illustrated in the accompanying drawings, described in the following specification and then more particularly pointed out in the claims which are appended hereto and form a part of this application.

With reference to the drawings, wherein we have illustrated the preferred embodiment of our invention as it is reduced to practice, and throughout the several views of which similar reference numerals designate corresponding parts, Figure 1 is a side elevation showing the preferred form of the invention with the various elements thereof in operative assembled position; Fig. 2 is a section on the line 2-2 of Fig. 1;

Fig. 3 is a top plan view of the machine, and Fig. 4 is a detail perspective view of one of the pounders and the bracket or casing in which it is mounted for reciprocation.

As has been heretofore explained, our invention consists essentially in a body member, which is formed in the nature of a tub-like receptacle, indicated at 10, and a supporting frame 11 in which the receptacle is removably mounted and which carries a seat or bracket 12 adapted to support an oil burner below the receptacle for the purpose of heating the water contained therein.

The body member 10 is, as stated, preferably, although not necessarily, constructed of sheet metal. This body member or tub 10 is stamped or pressed at its upper edge to produce threads so that the threaded flange 13 of the cover 14 may be quickly engaged with the upper edge of the tub and in sealing relation thereto for the purpose of preventing the escape of water during the washing of the clothes.

A relatively wide strip of wood or any other light material is, as indicated at 15, secured to the lower face of the cover 14 and extends as a diameter thereof. The reinforcing strip 15 is provided to brace the middle portion of the cover which is subjected to no little strain during the reciprocation of the pounders. These pounders, as will be hereinafter more fully explained, are adapted to reciprocate within the tub 10, and may be removed therefrom by removing the cover 14. The pounders are substantially identical in construction, and it is deemed necessary, therefore, to describe only one of them in detail. For this purpose, reference will be now had particularly to Fig. 4. As shown in this figure, each pounder includes a stem or shaft 16, which is freely received within a U-shaped supporting bracket or casing 17.

It is necessary, of course, to provide means for preventing the movement of the shaft 16 through the casing 17 to such an extent that the shafts will be withdrawn therefrom and for this reason we have provided for each terminal portion of the shaft a spring. These springs, designated individually by the numerals 18 and 19, are wound around the shaft and are of the type known as helical springs. The convolutions of these springs are of greater diameter than the width of the casing 17 so that their terminal convolutions may be engaged against the

adjacent edges of the adjacent terminals of the casing 17. A nut, indicated at 20, is threaded on the upper terminal of the shaft 16 and obviously holds the spring 18 against displacement. The lower spring 19 bears against the upper terminal of the pounding cup, indicated at 21, and is thus held against displacement from the shaft 16. The shaft 16 is held against lateral movement through 5 the casing 17 by means of the crank members 22 and 23. It will be noted upon reference to Fig. 4 that the eight portions 24 and 25 of the cranks are journaled in pairs of transversely aligned spaced apertures formed 10 in the side walls of the casing 17 so that these eight portions effect a closure of the open portion of the casing and thus prevent the lateral displacement of the shaft 16.

The arm 26 of the crank 23 is extended so 20 that it may project beyond the edge of the cover 14, as shown in Figs. 1 and 3. An L-shaped extension 27 is formed on the arm 26 and obviously serves as a handle whereby the crank 23 may be operated. It may be 25 well to explain at this point that the arm 28 of the crank 23 carries a pinion or gear-wheel 29 which is adapted to mesh with a gear-wheel carried by the other plunger crank so that the operator may by turning 30 the member 27 effect the simultaneous and opposed reciprocation of the two plungers, which are designated as entireties in Fig. 2 by the numerals 30 and 31.

It will now be noted upon reference particularly to Figs. 1 and 3 that the terminals 35 of the cranks of each of the plungers 30 and 31 are journaled in pairs of spaced brackets which are mounted on the cover-plate 14. The brackets in which the cranks 40 of the member 31 are journaled are designated individually by the numerals 32 and 33, while the brackets or bearings which receive the cranks of the plunger 30 are individually designated by the numerals 34 45 and 35. These brackets are substantially identical in construction, each consisting of a substantially triangular body portion 36 and a pair of terminally disposed laterally extending spaced flanges 37 and 38. These 50 flanges 37 and 38 are apertured and receive rivets or similar fastening devices 39 which are passed through the cover plate 14 and obviously tend to hold the body portions 36 in vertical position on the cover. The body- 55 plates 36 of the brackets 32 and 33 are transversely aligned as are the body plates of the members 34 and 35, but, as will be observed upon reference to Figs. 2 and 3, these pairs of brackets are arranged in staggered relation to each other so that a gear-wheel 40 which is keyed on the arm of the lower crank of the plunger 30 may mesh with the gear wheel 29 of the crank 23, which as shown in Fig. 3, is associated with 60 the plunger 31.

It is now to be noted that the terminals of the lower crank of the plunger 30 are arranged to rotate on the face of the cover 14 and are held in proper position therein by channeled bearing plates, indicated at 70 41. Similar bearing plates, indicated at 42, serve to hold the arms of the crank 23 in the proper position.

The foregoing description will make clear the manner in which the pounders are reciprocated, for it will be seen that the handle 27 of the crank 23 will produce the reciprocation of the U-shaped casing 17 through the slot or elongated opening 43 which is formed in the cover 14 and reinforcing member 15. It will also be noted that this reciprocating motion of the U-shaped casing 17 of the pounder 31 will be communicated to the pounder 30 by means of the gear-wheel 40 and the crank of the member 30 to which it is attached.

As will be noted upon reference to Figs. 1 and 2 the pounders are, when the machine is assembled, so arranged that their respective upward and downward movement 90 through the tub will be alternate. An opening 44 similar to the opening 43 is, of course, provided to receive the pounder 30, as best shown in Fig. 3.

The purpose in providing each of the U-shaped casings 17 with a pair of cranks will now become apparent for it will be noted that by equipping each of the U-shaped casings 17 with two cranks, these casings will be held at all times in vertical position and 100 will not be free to swing. Thus, while each of the pounding cups 21, which members will be hereinafter described in detail, moves through an ellipse during each reciprocation of the pounders 30 and 31 the shafts 105 16 of both pounders will at all times be in a vertical position so that the pressure exerted upon the clothes is always exerted in a vertical line and never at an acute angle 110 with respect to the bottom of the tub.

As will be apparent, the springs 18 and 19 operate not only to hold the shaft 16 against displacement upon the casing 17 but also serve as shock absorbers. When the cups 21 engage the clothes or the water 115 it is obvious that the spring 19 will yield and permit the shafts 16 to slide upwardly through the casing 17 and that when the cups are being withdrawn from the water the springs 18 will yield, permitting the 120 shafts 16 to slide downwardly through the casing 17 in response to the force of the suction, which will tend to hold the cups against withdrawal from the water.

The pounder cups are preferably formed 125 of sheet metal and are bell-shaped. The upper terminal of each of the cups is provided with a central aperture or orifice which receives the shafts 16. In the approximate center of each cup 21 is arranged 130

a diametrically extending pin or rod 45 which is directed through an opening or bore formed in the shaft and serves to hold the cup 21 against movement on the shaft.

5 The tub member is, as has been hereinbefore explained, removably mounted in a supporting frame or brace 11. This supporting frame 11 consists essentially in four quadrantly spaced metallic legs 46, the upper terminals of which are bolted or otherwise secured, as indicated at 47 to a sheet metal band 48. This band 48 is of an internal diameter equal to the external diameter of the tub 10 so that the lower terminals of the 10 tub may be snugly fitted within the band. In order to support the tub a second band or ring of metal, indicated at 49, is secured interiorly of the band 48 by the same fastening devices which are employed in holding 15 the legs 46.

It will be obvious upon reference to Fig. 2 that this ring 49 receives the lower edge of the tub and serves as a support therefor. The lower terminals of the legs 46 are connected to a pair of cross-braces, indicated at 25 50 and 51. The terminals of the members 50 and 51 are provided with lateral extensions which, as indicated at 52, are apertured to receive fastening devices 53 by 30 which they are secured to the leg members 46. On these cross braces 50 and 51 and at the point of intersection thereof is mounted the casing 12 which is adapted to receive an oil burner for the purpose of heating the 35 water contained within the tub 10. This member 12 is preferably formed in the nature of a cylindrical casing which is open at both ends and is slit on a number of longitudinal lines at its lower terminals so that 40 the metal may be bent to produce, the four laterally extending lugs or fingers 54, which are arranged to engage against the upper faces of the members 50 and 51, and the four quadrantly spaced containing fingers or 45 tongues 55, which are disposed, as shown in Fig. 1, to engage against the lower faces of members 50 and 51 at their point of intersection.

In reduction to practice it has been found 50 that the form of this invention, illustrated in the drawings and referred to in the above description, as the preferred embodiment, is the most efficient and practical; yet realizing that the conditions concurrent with the 55 adoption of this device will necessarily vary, it is desired to emphasize the fact that various minor changes in details of construction, proportion and arrangement of parts may be resorted to when required, without sacrificing any of the advantages of this invention, as defined in the appended claims.

Having thus described the invention, what is claimed as new is:—

1. A washing machine including a body 65 tub, a removable cover for the tub, a plu-

rality of pounders mounted for reciprocation through the cover and in the tub, each of said pounders including a casing, crank members for freely attaching the casing to the cover, a shaft slidably received within 70 the casing, and yieldable means for limiting the sliding movement of the shaft through the casing in both directions, said means being arranged upon opposite sides of the cover pounding cups carried by the lower 75 terminals of the shafts for engaging with the articles disposed in the tub, and manually operable means carried by the cover and connected to the cranks of the casing for reciprocating the pounders. 80

2. A washing machine including a tub having a removable cover, a pair of pounders mounted for reciprocation through the cover and in the tub, each of said pounders including a channel-shaped casing, a crank 85 member attaching the casing to the cover, a shaft removably mounted in the casing and held against lateral movement therefrom by the crank, a pair of springs wound about the shaft, there being a spring located at 90 each end of the shaft, said springs bearing against the terminals of the casing and being arranged upon opposite sides of the cover, a pounder cup carried by the lower terminal of the shaft, and means carried by 95 the upper end of the shaft for adjusting the tension of the springs, means operatively connecting the pounders, and means connected to one of the pounders for imparting reciprocatory movement to all of the pounders. 100

3. A washing machine including a body tub, a removable cover for the tub, said cover being provided with spaced elongated openings, bracket plates positioned at each longitudinal edge of the openings and extending 105 in parallel spaced relation to each other, a pounder mounted for reciprocation through each opening, each of said pounders including a channel-shaped casing, a pair of crank members having their eight 110 portions journaled in the side walls of the casing, the terminals of said crank members being journaled in the bracket plates, the cranks of the two pounders being arranged in parallel relation to each other, one crank 115 of one pounder having its terminal extended and bent to constitute an operating handle, the other terminal of said last-mentioned crank having a pinion, a pinion carried by the corresponding crank of the other 120 pounder and meshing with the first-mentioned pinion, shafts freely mounted in the said casing, pounder cups carried by the lower terminals of the shafts, and springs wound terminally about the shafts for yield- 125 ably resisting the movement of the shafts through the casing.

4. A washing machine including a body tub, a removable cover for the tub, said cover being provided with an elongated 130

opening, a bracket plate mounted at each longitudinal edge of the opening, said bracket plates being mounted in spaced relation to each other, a pounder mounted for reciprocation through the opening, said pounder including a channel-shaped casing, a pair of crank members having outwardly bent terminals, said terminals being journaled in the said bracket plates and arranged in longitudinally spaced relation, the eight portions of the cranks being rotatably mounted in the side walls of the casing, a shaft passing through the casing and held against lateral movement therein by the eight portion of the crank, a pounder cup carried by the lower terminal of the

shaft, a nut threaded on the other terminal of the shaft, helical springs wound about the shaft and interposed between the nut and the adjacent terminal of the casing and between the pounder cup and the adjacent terminal of the casing, and a handle formed on the lower of said crank members whereby the pounder may be operated. 20

In testimony whereof we affix our signatures in presence of two witnesses. 25
